BY ATTORNEYS

UNITED STATES PATENT OFFICE.

WILLIAM VELDEN, OF NEW ORLEANS, LOUISIANA.

DESIGN FOR A HORSESHOE.

SPECIFICATION forming part of Design No. 32,541, dated April 17, 1900.

Application filed March 17, 1900. Serial No. 9,116. Term of patent 14 years.

To all whom it may concern:

Be it known that I, WILLIAM VELDEN, a citizen of the United States, and a resident of New Orleans, in the parish of Orleans and State of Louisiana, have invented and produced a new and original Design for a Horseshoe, of which the following is a specification, reference being had to the accompanying drawing, forming a part thereof, in which is represented a perspective view of a horseshoe embodying the features of my design.

The feature of the design consists in interrupting a side outline of the horseshoe at the heel and connecting the interrupted portion

with the heel at the opposite side of the shoe by an angular bridge.

Having thus described my invention, I claim as new and desire to secure by Letters Patent—

The design for the horseshoe herein shown and described.

In testimony whereof I have signed my name to this specification in the presence of two subscribing witnesses.

WILLIAM VELDEN.
